FIGURE 1 is a top plan view of a smooth-walled service tray, for cooking utensils embodying our new design.

FIGURE 2 is a bottom plan view.

FIGURE 3 is a front elevational view.

FIGURE 4 is a side elevational view.

FIGURE 5 is an elevational view in section taken along line V—V of FIGURE 1.

FIGURE 6 is an elevational view in section taken along line VI—VI of FIGURE 1.

FIGURE 7 is a top plan view of a stepped-wall service tray for cooking utensils embodying our new design.

FIGURE 8 is a bottom plan view.

FIGURE 9 is a front elevational view.

FIGURE 10 is a side elevational view.

FIGURE 11 is an elevational view in section taken along line XI—XI of FIGURE 7.

FIGURE 12 is an elevational view in section taken along line XII—XII of FIGURE 7.

This application is a continuation of co-pending applications Serial Numbers 83,061 and 83,062 both filed December 17, 1964, now abandoned.

We claim:

The ornamental design for a service tray for cooking utensils or the like, as shown and described.
